ABSTRACT OF THE DISCLOSURE

A short-circuited waveguide illuminates a parabolic reflector from opposed slots in the broad walls adjacent to the short-circuiting plate. The waveguide is detachably secured to a reflector flange permanently attached to the reflector surface at a waveguide flange. The reflector flange has studs with heads that fit through openings in the waveguide flange. A locking ring is formed with slotted openings that fit over the studs and have a locking portion for gripping the underside of the stud heads when the locking ring is in locked position to keep the waveguide secured to the reflector.

The present invention relates in general to illuminating with electromagnetic energy and more particularly concerns novel methods and means for illuminating a reflector with microwave energy over an exceptionally wide frequency range with compact structure characterized by low windage, ease of assembly and adjustment, relatively low cost and quick connect-disconnect capabilities.

According to the invention, means are provided for supporting a length of waveguide from a reflector to be illuminated. Means are also provided for terminating the waveguide in a conducting plate that extends beyond the cross section of the waveguide in a plane substantially perpendicular to the waveguide axis. The waveguide wall is formed with aperture defining means closely adjacent to and generally parallel to the terminating conducting plate, thereby defining an electromagnetic energy path including the waveguide, the reflector and the aperture. The terminating conducting plate may include means defining an adjustable conducting element penetrating into the waveguide to an adjustable depth in a direction generally parallel to the waveguide axis in the vicinity of the plane passing through the aperture means for matching the impedance of the coaxing combination of the aperture defining means and the terminating conducting plate to the wave impedance of the waveguide.

Preferably the reflecting surface is defined by a conic section such as a parabola of revolution with the aperture means located substantially at the reflector focus. Preferably the waveguide is rectangular with its axis coinciding with the axis of symmetry of the reflector and with apertures symmetrically located in the opposed broad walls. Preferably the conducting terminating plate is circular with its center embracing the waveguide axis.

According to another feature of the invention there is a reflector flange attached to the reflector for receiving a waveguide flange to which the waveguide is secured. A locking ring is fastened to the waveguide flange. The waveguide flange is formed with openings supporting spring-loaded ball plungers that provide tension against the locking ring when properly positioned in the reflector flange and restrain the locking ring from rotating beyond the angle of detents machined in the locking ring.

For many years microwave systems have often employed reflectors, typically parabolic, with a suitable feed, such as a horn of "Cutler" type feed located at the focus to form a radiating system characterized by a desired di-

2

rectivity pattern, typically highly directional. Such systems have a number of disadvantages. Bandwidth is restricted. VSWR is less than that desired. Windage is relatively high. The moment of inertia is relatively high, a disadvantage of more importance when the reflector and feed assembly are rotated or oscillated to effect scanning.

Accordingly, it is an important object of this invention to overcome one or more of the preceding disadvantages.

More specifically, it is an object of this invention to provide an improved feed means for association with a reflecting surface characterized by relatively broad bandwidth, relatively low VSWR, relatively low moment of inertia, relatively low windage, relatively low cost, relative ease of manufacture, and relative ease of adjustment to obtain optimum electrical performance.

It is another object of this invention to achieve one or more of the preceding objects with a feed means that may be rapidly and easily connected or disconnected to facilitate assembly and disassembly in the field and permit rapid substitution of different feeds for different frequencies.

Numerous other features, objects and advantages of the invention will become apparent from the following specification when read in connection with the accompanying drawing in which:

FIG. 1 is a side view, partially in diametrical section of an embodiment according to the invention;

FIG. 2 is a top view of the detachable feed system according to the invention;

FIG. 3 is a view through section 3—3 of FIG. 2;

FIG. 4 is a side view of the assembly of FIG. 2;

FIG. 5 is an end view of the input flange secured to the waveguide;

FIG. 6 is a front view of the terminating conducting plate;

FIG. 7 is a back view of the reflector flange where attached to the reflector; and

FIG. 8 is a view of the locking ring face.

With reference now to the drawing and more particularly FIG. 1 thereof there is shown a side view, partially in diametrical section of a reflector and feed system according to the invention. Since important portions of the structure exhibit circular symmetry and top, side, front and back views fully disclose the construction of a preferred embodiment, such views are shown in the drawing to best illustrate the principles of the invention. Energy from an upper aperture 11 and lower aperture 12 in upper broad wall 13 and lower broad wall 14, respectively, of waveguide 15 illuminates parabolic reflector 16 with energy incident through waveguide input opening 17 of reflector flange 21. Reflector flange 21 is shown permanently fastened to the central rim 22 of reflector 16 by welding or other suitable mechanical techniques. Reflector flange 21 may be formed with a recess as shown for accommodating a pressure window 23. Reflector flange 21 is also preferably formed with a channel 24 comprising a quarter wavelength choke.

Reflector flange 21 is also preferably formed with tapped openings, such as 25, for accommodating a threaded stud, such as 26, that guides waveguide flange 31 into nesting relationship in reflector flange 21 as illustrated. Waveguide flange 31 may also be formed with a recess for accommodating a pressure window 32. Waveguide flange 31 includes openings for accommodating studs, such as stud 26, and tapped holes for accommodating retainer screws, such as 33. Waveguide flange 31 is formed with an annular shoulder 34 for accommodating locking ring 35 that keeps waveguide flange 31 securely seated in reflector flange 21 by gripping the heads of studs, such as stud 26, in a manner which will be better understood from the discussion which follows.

Waveguide 15 is preferably soldered or braised to waveguide flange 31 and terminates in a radiating section 36 with opposed narrow walls slightly narrower than the narrow walls of the rest of the waveguide by exactly one wall thickness. Radiating section 36 includes slits 11 and 12 in broad walls 13 and 14 comprising aperture defining means and is terminated in conducting end plate 37. Conducting plate 37 includes an axially located matching screw 41 with a lock nut 42 and may also function to fasten circular end plate 37 to a cap placed over the end of waveguide section 36. It may be desirable to employ additional screws such as 61, 62 and 41 to achieve optimum matching. Slits 11 and 12 preferably have the dimensions indicated in fractions of air wavelength at center frequency when covered by material having a dielectric constant of the order of 2.2. Note that the slit width is much less than a quarter wavelength while the slit length is greater than a quarter wavelength and less than a half wavelength at the center frequency of the operating range.

Referring to FIG. 2, there is shown a top view of the detachable waveguide feed assembly. Like reference symbols are used to identify corresponding elements throughout the drawing. FIG. 2 also illustrates a detail of how one of the three unequiangularly spaced spring loaded ball plungers, like 43 in waveguide flange 31, detent lock in a mating recess, such as 44 in locking ring 35.

Referring to FIG. 3, there is shown a view through section 3-3 of FIG. 2 helpful in understanding how the quick connect-disconnect mechanism functions. Opposed screws 33 and 33' keep locking ring 35 secured to waveguide flange 31, prohibiting any substantial axial movement of the locking ring while allowing angular movement through substantially 15 degrees determined by the angular width of slots 51 and 52. This arrangement allows locking ring 35 to be rotated between unlock position and the lock position shown in FIG. 3 in which locking studs 26, 26' and 26'' have their respective heads bearing against the beveled inner surface of slots 53, 54 and 55, respectively. Unlocking and locking is facilitated by the diametrically opposed fingers 56 and 57. To unlock the waveguide feed section it is only necessary to apply a counterclockwise torque to fingers 56 and 57 until the clockwisemost portions of slots 53, 54 and 55 are aligned with the heads of studs 26, 26' and 26''. In this position, the three angularly spaced spring loaded balls lock in three corresponding detents, 44, 44' and 44'', in locking ring 35, thus securing locking ring 35 in the remove or unlock position. Then grasping the waveguide feed assembly 15, it may be withdrawn from the reflector assembly because the heads of studs 26, 26' and 26'' clear the clockwisemost openings in slots 53, 54 and 55. The reverse procedure is practiced to quickly connect the waveguide feed assembly. That is, the assembler grasps fingers 56 and 57, aligns the clockwisemost openings of slots 53, 54 and 55 over the heads of studs 26, 26' and 26'', seats the assembly so that waveguide flange 31 is nested in reflector flange 21 and then rotates fingers 56 and 57 clockwise until the three spring loaded ball plungers like 43 snap into a corresponding recess such as 44a, 44a' and 44a'' in locking ring 35, rapidly securing the assembly into position with a secure mechanical and electrical coupling to the reflector assembly.

FIG. 8 illustrates the face of ring 35 showing recesses 44, 44' and 44'' which facilitate maintaining the unlock position. Detent positions 44a, 44a' and 44a'' are used to maintain the lock position.

Referring to FIG. 4, there is shown a side view of the waveguide feed assembly. Referring to FIG. 5, there is shown a back view of the assembly of FIG. 4 better illustrating the openings 53', 54' and 55' through which screws 26, 26' and 26'' pass when the waveguide assembly is nested in position and reflector flange 21 together with a view of the orientation of ball plungers 43, 43' and 43'', respectively, in openings 44, 44' and 44'', respectively, of locking ring 35.

Referring to FIG. 6, there is shown a front view of terminating conducting plate 37 showing screw 41 and locking nut 42. There is also shown two openings 61 and 62 along a line generally parallel to the broad walls of the waveguide symmetrical about screw 41 for accommodating an additional pair of screws like 41 to help improve the impedance match. Adjustment of screw 41 is accomplished by energizing input 17 through impedance measuring means, such as a slotted waveguide, and adjusting screw 41 until a minimum VSWR is measured. To allow for mechanical tolerances in production, provision for additional screws in openings 61 and 62 permits "fine" impedance matching for low VSWR by screw adjustment at these points.

Referring to FIG. 7, there is shown an end view of the reflector flange 21 showing the four tapped holes 63, 64, 65 and 66 for receiving screws that secure a mating flange from a rectangular waveguide that exchanges energy with the invention and external transmitting and/or receiving apparatus.

The invention has a number of electrical and mechanical advantages. The operating band width is of the order of 18% with a VSWR attainable of less than 1.2. Exceptionally good illumination of the reflecting surface is obtained because the slits 11 and 12 closely approximate a point source centered substantially midway between the slits 11 and 12 with conducting plate 37 imaging slits 11 and 12 into virtual sources that confine almost all the energy emitted from slots 11 and 12 to impinging upon reflector 16. To this end it is preferable that the angle of radiated energy beyond the axis of the waveguide 15 contains approximately 90% of the power available to illuminate the parabolic reflector, and this angle corresponds substantially with the angle subtended by the axis and periphery, measured from the focus. Reflector plate 37 diameter is chosen to satisfy the above criteria.

The structure is relatively easy and inexpensive to fabricate, lightweight, rugged and characterized by relatively low windage and moment of inertia because the only structure in addition to the waveguide is conducting plate 37 and the tuning screws, and these elements extend only slightly beyond the distance for the reflector 16 to the focus. And the quick connect-disconnect feature facilitates rapid assembly and disassembly, even under severe combat conditions in the field. This feature also facilitates changing waveguide feed assemblies for achieving optimum performance at a given frequency.

An actual embodiment of the invention is the commercially available DICO type AN2M-4 dish and feed operative over the frequency range of 10.7-13.3 GHz. with a dish 4 feet in diameter having a focus of 18 inches from the dish surface along the dish axis. The VSWR was less than 1.15 over this frequency range.

There has been described a novel waveguide feed for an associated reflector. It is evident that those skilled in the art may now make numerous modifications and uses of and departures from the specific embodiment described herein without departing from the inventive concepts. Consequently, the invention is to be construed as embracing each and every novel feature and novel combination of features present in or possessed by the apparatus and techniques herein disclosed and limited solely by the spirit and scope of the appended claims.

What is claimed is:

1. Apparatus for radiating electromagnetic energy comprising,
hollow conducting means defining a waveguide closed at one end by means including a conducting plate generally perpendicular to the axis of said waveguide and extending beyond the perimeter thereof, said hollow conducting means being formed with slit means defining an aperture closely adjacent to said conducting plate for exchanging energy between the interior of said waveguide and means external to said waveguide intercepting a beam having an apex em-

braced by said aperture and directed away from said waveguide and said conducting plate toward the other end of said waveguide.

said means external to said waveguide comprising means defining a reflecting surface having at least one focus embraced by said slit means,

said means defining a reflecting surface having means for detachably securing said waveguide thereto,

said means for detachably securing including, means defining a reflector flange permanently attached to 10 said reflector surface,

a plurality of stud means angularly spaced about the waveguide axis permanently secured to said reflector flange each formed with head means, and

further comprising means defining a waveguide flange 15 at said other end for mating relationship with said reflector flange and formed with a plurality of clearing openings angularly spaced about the waveguide axis each arranged for receiving a corresponding one of said studs whereby with said waveguide flange seated in mating relationship with said reflector flange, said studs maintain said flanges in fixed angular relationship with said heads protruding outside said clearing openings,

locking ring means formed with a plurality of circumferentially slotted openings each having a clearance portion arranged to coincide with a respective one of said clearing openings when said locking ring means is in an unlock position permitting relative displacement between said flanges along the waveguide axis 20 and a contiguous locking portion for gripping the underside of a respective head when said locking ring means is in a lock position preventing relative displacement between said flanges along the waveguide axis, and

means for securing said locking ring means to said waveguide flange,

said means for securing including means for establishing limited relative angular displacement between said locking ring means and said waveguide flange about 30 the waveguide axis between said lock position and said unlock position.

2. Apparatus for radiating electromagnetic energy in accordance with claim 1 wherein said waveguide is a rectangular waveguide having at least opposed broad walls and said slit means defines opposed apertures in respective ones of said broad walls oriented with aperture length generally parallel to said conducting plate, aperture width much less than said aperture length and aperture spacing from said conducting plate less than said aperture length. 35

3. Apparatus for radiating electromagnetic energy in accordance with claim 2 wherein said rectangular waveguide is dimensioned to propagate energy over a band centered about a frequency corresponding to a predetermined wavelength,

said aperture length being less than a half and more than a quarter of said predetermined wavelength,

said aperture width being much less than a quarter of said predetermined wavelength.

4. Apparatus for radiating electromagnetic energy in accordance with claim 3 wherein said aperture length corresponds to substantially 0.4 said predetermined wave-

length and said aperture width corresponds to substantially 0.1 said predetermined wavelength.

5. Apparatus for radiating electromagnetic energy in accordance with claim 3 wherein said conducting plate is circular and has its center on the axis of said waveguide.

6. Apparatus for radiating electromagnetic energy in accordance with claim 1 and further comprising, rod-like means passing through said conducting plate into said waveguide generally parallel to the waveguide axis adjacent to said slit means for reducing reflected energy in said waveguide.

7. Means for detachably securing a waveguide comprising, means defining a first flange formed with an opening embracing said waveguide axis,

a plurality of stud means angularly spaced about the waveguide axis permanently secured to said first flange each formed with head means,

means defining a second flange formed with an opening embracing said waveguide axis for mating relationship with said first flange and formed with a plurality of clearing openings angularly spaced about the waveguide axis each arranged for receiving a corresponding one of said studs whereby with said second flange seated in mating relationship with said first flange, said studs maintain said flanges in fixed angular relationship with said heads protruding outside said clearing openings,

locking ring means formed with a plurality of circumferentially slotted openings each having a clearance portion arranged to coincide with a respective one of said clearing openings when said locking ring means is in an unlock position permitting relative displacement between said flanges along the waveguide axis and a locking portion for gripping the underside of a respective head when said locking ring means is in a locked position preventing relative displacement between said flanges along the waveguide axis and a locking portion for gripping the underside of a respective head when said locking ring means is in a locked position preventing relative displacement between said flanges along the waveguide axis, and

means for securing said locking ring means to said second flange,

said means for securing including means for establishing limited relative angular displacement between said locking ring means and said second flange about the waveguide axis between said locking position and said unlocked position.
